HYDRAULIC CUTTING MACHINE

William J. Riddle, Mount Gilead, Ohio, assignor
to The Hydraulic Development Corporation,
Inc., Wilmington, Del., a corporation of Dela-
ware

Application March 28, 1941, Serial No. 385,717

15 Claims. (Cl. 164—56)

This invention relates to hydraulic machinery and, in particular, to hydraulically operable cutting machines.

It is an object of the invention to provide a cutting machine with a hydraulically operable cutter and a hydraulic work piece holder, in which the work piece holder is operable hydraulically without actuation of the cutter.

Another object of the invention consists in the provision of a hydraulic cutting machine, in which the operation of the cutter is automatically initiated in response to a predetermined pressure with which the work piece to be cut is pressed upon a support therefor.

It is another object of the invention to provide a cutting machine, in which the last portion of the cutting stroke is slowed down.

It is another object to provide a cutting machine, in which the cutter is hydraulically operated by a fluid motor having advancing means and retracting means, and in which fluid expelled from said retracting means during the operation of said advancing means is used for assisting the latter.

Still another object consists in the provision of a cutting machine comprising a fluid motor with advancing and retracting means, in which the release of fluid from the retracting means of said fluid motor is responsive to the admittance of pressure fluid to the advancing means of said motor.

It is a still further object of the invention to provide a cutting machine with a fluid motor having advancing and retracting means, in which a pilot unloader valve is provided for allowing release of fluid from said retracting means only when a predetermined pressure has built up in said advancing means.

These and other objects and advantages of the invention will appear more clearly from the following specification in connection with the accompanying drawings, in which:

Figure 1 is a front view of a hydraulically operable cutting machine according to the invention.

Figures 2 and 3 illustrate valves used in the hydraulic circuit of the present invention.

Figure 4 illustrates diagrammatically the hydraulic circuit of a cutting machine according to the invention.

Structural arrangement

Referring to the drawings in detail, the cutting machine shown therein comprises a pair of main cylinders 1, each of which has reciprocably

mounted therein a piston 2 with a piston rod 3. The said cylinder pistons and piston rods are substantially equal. Connected to the piston rods 3 in any convenient manner is the cutter bar 4 for cutting the work piece.

The main cylinders 1 are stationary and supported by the press head 5 which is spaced from and connected in any convenient manner with the press bed 6 for supporting the work piece. A work piece placed on the press bed 6 is clamped or held thereagainst by means of hold-down cylinders 7, the effective number of which may be varied according to the size of the work piece, which may be sheet metal, paper, or the like.

Reciprocably mounted in each hold-down cylinder 7 is a piston 8 with a piston rod 9 adapted to engage the work piece. Between the lower surface of the piston 8 and the bottom of the cylinder 7 is arranged a spring 10 for lifting or returning the piston 8 to its initial position when the hold-down or clamping operation has been completed.

The upper portion of each of the hold-down cylinders 7 communicates with a conduit 11 leading into a common conduit 12 which in its turn is connected to a conduit 13, comprising an adjustable choke 14. The opening in the choke valve 14 determines the rate at which pressure fluid enters the hold-down cylinders 7. The conduit 13 leads to an adjustable admission valve 15 of the type shown in Figure 2, which valve will be described in detail later.

Communicating with the admission valve 15 is a conduit 16 leading into a conduit 17, which 35 communicates with the upper portion of the two main cylinders 1. The lower portion of the main cylinders 1 is adapted to communicate with each other through a conduit 18. The ports 19 at which the conduit 18 communicates with the 40 main cylinders 1 are adapted to be by-passed by conduits 20 pertaining to each of the main cylinders 1 comprising a choke valve 21, and communicating with a conduit 22 respectively leading into the cylinders 1 adjacent the bottom 45 portion thereof. Each of the conduits 22 comprises a check valve 23, which opens in the direction of the respective arrow.

The admission valve 15 may be by-passed by a conduit 24 comprising a check valve 25 and 50 communicating with its conduits 16 and 13a respectively, which latter is connected to the admission valve 15. Connected to the conduit 18 is a conduit 26 leading to a pilot unloader valve 27 of the type shown in Figure 3, which will likewise be described later. A pilot line 28 in-

terconnects the pilot unloader valve 27 and the conduit 13a. A further conduit 29 comprising a check valve 30 also leads from the pilot unloader valve 27 to the conduit 13a, which is connected to a four-way valve 31.

Also connected to the four-way valve 31 is a conduit 32 comprising a shutoff valve 33 and a check valve 34 and leading to the conduit 26. A further conduit 35 leads from the four-way valve 31 to a fluid reservoir or surge tank 36, which is connected with the pilot unloader valve 27 through a leakage line 37. Furthermore connected with the tank 36 is a conduit 38 comprising a needle valve 39 and leading to the conduit 26. Another line, 40, comprising a check valve 41 is adapted to effect communication between the tank 37 and the conduit 17. The tank 36 is also connected with a conduit 42 leading to the suction side of a pump 43, the pressure side of which is connected to the conduit 44 comprising a pressure relief valve 45, which in its structure may correspond to the valve shown in Figure 2.

The relief valve 45 is adapted to communicate on one hand through conduit 46 with the tank 36 and on the other hand through conduit 47 with the four-way valve 31. The four-way valve 31 is so arranged that when its valve member (not shown) is moved into its left-hand end position with regard to Figure 4, the conduit 47 communicates with the conduit 13a, whereas when the valve member of the four-way valve 31 is shifted to its right-hand end position, the conduit 47 communicates with the conduit 32. When the valve member of the four-way valve 31 is in its intermediate position, the conduit 47 communicates with the conduit 35. The four-way valve 31 does not form a part of the present invention and for a more detailed description thereof, reference may be had to Patent No. 2,109,162 to Boehle. The valve member of the valve 31 is connected with a shift arm 48 pivotally connected at 49 with a three-arm lever, generally designated 50, and shiftable about the pivot 51. The arm 52 of the lever 50 is pivotally connected with an armature 54 which is electrically connected with the lines 55 and 56 adapted respectively to be connected with the lines 57 and 58 by closure of the switch blades 59 and 60.

The switch blades 59 and 60 pertain to an armature 61 which carries a third switch blade 62 adapted to electrically connect the line 63 comprising a normally closed limit switch 64 and leading to the main supply line 65 with the line 66 connected to one end of the solenoid 67. The solenoid 67 is furthermore connected with a line 68 adapted by closure of the push button 69 to be electrically connected with the line 70 leading to the main supply line 65. The other end of the solenoid 67 is connected, by means of line 71, with the main supply line 72, which is also connected with the line 58.

The arm 73 of the three-arm lever 50 is continuously urged in anti-clockwise direction by means of a spring 74 attached to the arm 73, which arm is also pivotally connected to a push rod 75. The push rod 75 has adjustably mounted thereon a collar 76 adapted to be engaged by an arm 77 carried by the cutter bar 4. Also carried by the cutter bar 4 is an adjustable abutment screw 78, which is preferably so adjusted that it opens the limit switch 64 after the cutter bar 4 has completely cut the work piece and

75 moved beyond the same by a predetermined distance.

Referring now to the valve of Figure 2, the same comprises substantially a casing 79 which is joined to a valve housing 80, for instance, by a threaded connection. Reciprocably mounted partly within the casing 79 and the valve housing 80 is a plunger 81 which is free to move up and down against the pressure of a compression spring 82, which makes contact against the head 83 on the plunger 81. The compression spring 82 may be adjusted to any desired pressure by rotating the adjusting screw 84, which pushes the spring cap 85 downwardly against the compression spring 82. The adjustment is maintained in locked position by the lock nut 86.

Contained within the upper part of the valve housing 80 is a plunger lifting chamber 87 through which the plunger 81 passes. Within this chamber, the plunger diameter is enlarged to form the differential lifting area 88 which is of annular form. One side of the plunger lifting chamber 87 has the inlet port 89 passing through the walls of the valve housing 80 where it continues in the pilot line 28 (Figure 4).

The chamber 90 below the lower end of the plunger 81 is connected with the conduit 29. The valve chamber 91 of the valve housing 80 is connected with the conduit 26, while the casing 79 is connected with the leakage conduit 37 leading to the tank 36. The device of Figure 2 operates in such a manner that when the pressure in the plunger lifting chamber 87 reaches a predetermined value, the plunger 81 is lifted by the fluid acting on the lifting area 88 so that fluid from conduit 26 may pass through the valve chamber 91 into the conduit 29.

Referring to Figure 3, the valve shown therein is somewhat similar to the valve of Figure 2, and similar parts are, therefore, designated with the same reference numerals, however, with the additional letter *a*. In contrast to the valve of Figure 2, the valve chamber 91a communicates on one hand with the conduit 13 and on the other hand with the conduit 13a so that a continuous connection is established between the conduits 13 and 13a, irrespective of the position of the plunger 81a. The chamber 90a below the lower end of the plunger 81a communicates with the conduit 16. When a predetermined pressure is built up in the valve chamber 91a, this pressure acts on the lifting area 88a, thereby lifting the plunger 81a and establishing communication between the conduit 16 and the conduits 13 and 13a.

Operation

Assuming that all parts of the device shown in the drawings occupy the position of Figure 4, and that it is now desired to start a working cycle, the operator pushes the push button 69, thereby closing a circuit comprising the main supply line 65, lines 70 and 68, solenoid 67, line 71 and main supply line 72. As a result thereof solenoid 67 is energized and causes the armature 61 to move upwardly so that the switch blade 62 establishes a holding circuit for the solenoid 67, while the switch blades 59 and 60 close the energizing circuit for the solenoid 54. As a result of the energization of the solenoid 54, the armature 53 shifts the three-arm lever 50 in clockwise direction so that by means of the switch arm 48, the valve member (not shown) of the four-way valve 31 is moved into its right-hand end position with regard to Figure 4. This shifting movement

establishes connection between the conduit 47 and the conduit 13a, while simultaneously establishing connection between the conduits 35 and 32.

Assuming that previously the pump 43 was started, pressure fluid is now delivered by the pump 43 through the conduit 47, the four-way valve 31, the conduit 13a, valve chamber 91a of the valve 15, the conduits 13 and 12 and into the hold-down cylinders 7 where the pressure fluid acts upon the respective pistons 8 and moves the latter downwardly against the thrust of the springs 10 so that the piston rods 9 grip the work piece to be cut.

When a predetermined pressure has built up in the cylinders 7 so that the work piece is pressed with a predetermined pressure against its support or press bed 6, this pressure overcomes the thrust of the spring 82a so that the plunger 81a is lifted, thereby establishing connection between the conduit 16 and the conduits 13 and 13a. As a result thereof, pressure fluid from the conduit 13a now passes through conduit 16 into the conduit 17 from where it flows into the main cylinders 1 above the pistons 2. This pressure acting upon the pistons 2 causes the latter to compress the fluid in the main cylinders 1 below the pistons 2 which, up to this time, could not escape since the check valve 34 allows passage of fluid only in the direction indicated by the arrow pertaining thereto, while the needle valve 39 is closed and the plunger 81 of the valve 27 is in its lower position, in which it prevents communication between the conduits 26 and 29. However, since the pressure, now acting upon the pistons 2 and conveyed thereto through the conduit 17, also prevails in the pilot line 28, this pressure is conveyed into the lifting chamber 87 where it acts upon the lifting area 88 and lifts the plunger 81 so as to effect communication between the conduits 26 and 29. As a result thereof, fluid is now expelled from the lower portion of the main cylinders 1 into the conduit 26 from where it passes through the valve 27 and check valve 30 into the conduit 29, and is then conveyed through the conduit 13a, the valve 15 and the conduits 16 and 17 into the upper portion of the main cylinders 1. In other words, the pressure fluid expelled by the pistons 2 aids the downward movement of the said pistons.

As will be seen from the drawings, before the pistons 2 have completed their downward stroke, i. e., preferably before they have completely cut through the work piece, the pistons 2 close the ports 19 so that the fluid beneath the pistons 2 can escape from the main cylinders 1 only through the conduits 22, the choke valves 21 and the conduits 20 into the conduit 18. Depending on the adjustment of the choke valves 21, the last portion of the downward movement or cutting stroke of the pistons 2 may be slowed down to any desired degree. This slow-down movement prevents any damage to the work piece, which otherwise might be caused if the cutter bar 4 cuts through the work piece at a high speed and then suddenly meets no further resistance.

When the cutter bar 4 has completely cut through the work piece and moved beyond the same by a predetermined distance, the abutment screw 18 (Figure 1) engages and opens the limit switch 64, thereby breaking the holding circuit for the solenoid 67. As a result thereof, the armature 61 with its blades 62, 59 and 60 drops back to its open position, thereby deenergizing the

solenoid 54. The spring 14 then shifts the three-arm lever 58 in anti-clockwise direction and by means of the shift arm 48 shifts the valve member of the four-way valve 31 into its left-hand end position, thereby establishing hydraulic connection between the conduits 47 and 32, while simultaneously effecting communication between the conduits 13a and 35. Pressure fluid is now delivered by the pump 43 through conduit 47, four-way valve 31, conduit 32, the open shutoff valve 33, check valve 34, conduits 26, 18 and 20, check valves 23 and conduits 22 into the lower portion of the main cylinder 1. Consequently, the pistons 2 start their upward or retraction movement, while expelling the fluid in the upper portion of the main cylinders 1 into the conduit 17, from where it flows through conduits 16 and 24, check valve 25, conduit 13a and the conduit 35 into the tank 36.

20 Since, due to the hydraulic communication now established between the conduits 13a and 35, a pressure drop occurs in the conduits 13 and 12, the springs 10 beneath the hold-down pistons 8 immediately return the cutter bar 4 to its lifted position, thereby enabling the operator to remove the cut off portion of the work piece and to place the work piece into a new position for a further cut, while the cutter bar 4 is still moving to its retracted position.

25 Due to the pressure drop in the conduit 13a, the pressure in the pilot line 28 likewise drops so that the compressing spring 82 of the valve 27 again causes the plunger 81 to close the hydraulic communication between the conduits 26 and 29.

30 When the pistons 2 and the cutter bar 4 connected thereto have reached a predetermined position during the said retraction stroke, the arm 77 engages the collar 76, thereby lifting the push rod 75 so that the latter, through the intervention of the three-arm lever 58 and the shift arm 48, moves the valve member of the four way valve 31 to its intermediate position, in which the conduit 35 is connected with the conduit 47. 35 When this connection has been established, the pressure fluid delivered by the pump 43 is merely circulated through the conduit 47, the four-way valve 31, conduit 35 and tank 36, from where it flows through the conduit 42 to the suction side 40 of the pump 43. As a result the pistons 2 and, therefore, the cutter bar 4 come to a halt.

35 Since, as previously mentioned, the pilot unloader valve 27 had closed the hydraulic connection between the conduits 26 and 29, the pressure in the lower portion of the main cylinders 1 is maintained and the pistons 2 are held in their lifted position. A new cycle may then be started by again actuating the push button 69.

40 In order to assist in setting up the cutter bar 4, provision is made to inch the cutter bar slowly downwardly. To this end the shutoff valve 33 is closed to prevent fluid from entering into the lower portion of the main cylinders 1 if the pump is running. The needle valve 39 may then be opened to allow the weight of the pistons 2 to expel any desired restricted quantity of fluid from the lower portion of the main cylinders 1 into the conduits 18, 26 and 38, from where the fluid may pass into the tank 36. In this way any gradual downward movement of the pistons 2 and the cutter bar 4 connected thereto may be effected. Fluid is supplied to the upper portions of the main cylinders 1 through the small check valve 41. If, for some reason, any undue pressure

should develop in the conduit 44 or the conduit 47, this pressure will be released into the tank 36 through the valve 45 which, as previously mentioned, corresponds in its construction to that of the valve 15.

It will be understood that I desire to comprehend within my invention such modifications as come within the scope of the claims and the invention.

Having now fully described my invention, what I claim as new and desire to secure by Letters Patent is:

1. In a hydraulically operable cutting machine, a main plunger having associated therewith fluid operable advancing and retracting means for reciprocating said plunger, cutting means operatively connected with said main plunger, a fluid operable auxiliary plunger for holding a work piece to be cut, and valve means controlling the admittance of pressure fluid to said advancing means in response to a predetermined pressure on said auxiliary plunger.

2. In a hydraulically operable cutting machine, a main plunger having associated therewith fluid operable advancing and retracting means for selectively advancing or retracting said plunger, cutting means operatively connected with said main plunger, a fluid operable holding plunger movable independently of said main plunger for holding a work piece to be cut, said holding plunger being adapted hydraulically to be connected with said advancing means, and pressure responsive means responsive to a predetermined pressure on said holding plunger for establishing hydraulic connection between said holding plunger and said advancing means.

3. In a hydraulically operable cutting machine, a cylinder, a double-acting plunger reciprocably mounted in said cylinder, cutting means operatively connected with said plunger, a fluid source adapted to supply pressure fluid to said cylinder for actuating said plunger, work piece holding means for holding a work piece during the cutting operation, fluid operable advancing means associated with said work piece holding means for advancing the same, conduit means for conveying pressure fluid from said fluid source to said fluid operable advancing means independently of the supply of pressure fluid to said cylinder, yielding means associated with said holding means and constantly urging said holding means into retraction position, and fluid pressure responsive means responsive to a predetermined pressure on said work piece holding means for establishing hydraulic connection between said fluid source and one side of said cylinder and for conveying fluid expelled from the other side of said cylinder to said first mentioned side of said cylinder to assist the advancing movement of said plunger.

4. In a hydraulically operable cutting machine, a main plunger having associated therewith fluid operable advancing and retracting means for selectively advancing or retracting said plunger, cutting means operatively connected with said main plunger, a fluid operable holding plunger movable independently of said main plunger for holding the work piece to be cut, said holding plunger being adapted hydraulically to be connected with said advancing means, pressure responsive means responsive to a predetermined pressure on said holding plunger for establishing hydraulic connection between said holding plunger and said advancing means and between the latter and said retracting means, and valve

means hydraulically connected with said pressure responsive means for allowing flow of fluid from said retracting means to said advancing means, while preventing the flow of fluid in the reverse direction.

5. In a hydraulic system for a cutting machine, a main plunger having associated therewith fluid operable advancing and retracting means for reciprocating said plunger, a fluid operable auxiliary plunger, conduit means for hydraulically interconnecting said advancing means and said auxiliary plunger, means arranged in said conduit means and responsive to a predetermined pressure on said auxiliary plunger for effecting hydraulic connection between said advancing means and said auxiliary plunger, and valve means hydraulically connected with said retracting means for preventing escape of fluid from said retracting means prior to the establishment of said predetermined pressure to prevent accidental advancing movement of said main plunger.

6. In a hydraulically operable cutting machine, a main cylinder, a double-acting main plunger reciprocable in said main cylinder, a cutter bar operatively connected with said main plunger, an auxiliary fluid operable plunger for holding a work piece during the cutting operation, a fluid source adapted to supply pressure fluid to said main plunger and said auxiliary plunger, conduit means for hydraulically interconnecting said fluid source with said plunger, valve means in said conduit means for sequentially admitting pressure fluid from said fluid source first to said auxiliary plunger and thereafter to said main plunger, and fluid pressure responsive means hydraulically connected with the retraction side of said main plunger and responsive to a predetermined pressure on the advancing side of said main plunger for conveying pressure fluid expelled from the retraction side of said main plunger to the advancing side thereof.

7. In a hydraulically operable cutting machine, a main cylinder, a double-acting main plunger reciprocably mounted in said main cylinder, cutting means operatively connected with said main plunger, said main cylinder having two ports spaced in the longitudinal direction of said main cylinder, choke means associated with one of said ports for restricting the escape of fluid from said main cylinder when said main plunger approaches the end of its cutting stroke, an auxiliary fluid operable plunger for holding a work piece during the cutting operation, and valve means hydraulically connected with said auxiliary plunger and adapted to prevent the supply of pressure fluid to the advancing side of said main plunger prior to the establishment of a predetermined pressure on said auxiliary plunger.

8. In a hydraulically operable cutting machine, a main cylinder, a double-acting main plunger reciprocably mounted in said main cylinder, cutting means operatively connected with said main plunger, said main cylinder having two ports spaced in the longitudinal direction of said main cylinder, choke means associated with one of said ports for restricting the escape of fluid from said main cylinder when said main plunger approaches the end of its cutting stroke, by-pass valve means for by-passing said choke means in response to supply of pressure fluid to the retraction side of said plunger, an auxiliary fluid operable plunger for holding a work piece during the cutting operation, and control valve means hydraulically connected with said auxiliary plunger and adapted to prevent the supply of

pressure fluid to the advancing side of said main plunger prior to the establishment of a predetermined pressure on said auxiliary plunger.

9. In a hydraulically operable cutting machine, a main plunger having fluid operable advancing and retracting means associated therewith for activating said main plunger, cutting means operatively connected with said main plunger, a fluid operable auxiliary plunger for holding a work piece to be cut, a pressure fluid source for supplying pressure fluid selectively to said main plunger or to said auxiliary plunger, control valve means hydraulically connected with said fluid source for preventing hydraulic communication between the latter and the advancing side of said main plunger prior to the establishment of a predetermined pressure on said auxiliary plunger, and by-pass valve means for hydraulically by-passing said control valve means during the retraction stroke of said main plunger to effect hydraulic communication between said advancing means and said fluid source.

10. In a hydraulically operable cutting machine, a main plunger, fluid operable advancing and retracting means associated with said plunger for actuating the same, cutting means operatively connected with said main plunger, a fluid operable auxiliary plunger for holding a work piece to be cut, a fluid reservoir, a pressure fluid pump having its suction side connected with said reservoir and adapted selectively to supply pressure fluid to said auxiliary plunger and said advancing means or to said retracting means, first conduit means connecting said fluid reservoir with said advancing means, a check valve arranged in said first conduit means and adapted to admit fluid from said reservoir to said advancing means, but not vice versa, controlling means for sequentially admitting pressure fluid to said auxiliary plunger and said advancing means, second conduit means adapted to supply pressure fluid from said pump to said retracting means, a shutoff valve in said second conduit means for interrupting hydraulic communication between the pressure side of said pump and said retracting means, third conduit means adapted to establish hydraulic communication between said retracting means and said reservoir, and adjustable choke means for varying the rate of flow of fluid from said retracting means to said reservoir.

11. In a hydraulically operable cutting machine, a main plunger having associated therewith fluid operable advancing and retracting means for reciprocating said plunger, cutting means operatively connected with said plunger, a fluid operable auxiliary plunger for holding a work piece during the cutting operation, a pressure fluid source for supplying pressure fluid selectively to said auxiliary plunger and said advancing means or to said retracting means, fluid pressure responsive means hydraulically connected with said fluid source for admitting pressure fluid to said advancing means in response to a predetermined fluid pressure on said auxiliary plunger, and yielding means responsive to the release of fluid pressure on said auxiliary plunger for spacing the same from the work piece.

12. In a hydraulically operable cutting ma-

chine, a main plunger having associated therewith fluid operable advancing and retracting means for actuating said plunger, a constant delivery pump adapted selectively to supply pressure fluid to said advancing and retracting means, a four-way valve adapted selectively to connect said pump with said advancing means or said retracting means or to by-pass the delivery of said pump to an exhaust, cutting means operatively connected with said main plunger, an auxiliary plunger adapted hydraulically to be connected with said pump to exert holding pressure on a work piece to be cut, fluid pressure responsive means hydraulically connected with said auxiliary plunger and adapted in response to a predetermined pressure on the latter to effect hydraulic communication between the advancing side of said main plunger and said pump, and valve means operable in response to a predetermined point of travel of said main plunger after completion of the cutting operation for reversing hydraulic communication between said pump and said advancing and said retracting means.

13. In a hydraulically operable cutting machine, a plurality of double-acting main plungers, cutting means operatively connected with said main plungers, conduit means connecting the advancing sides of said main plungers and being adapted hydraulically to be connected with the pressure side of a pressure pump, a plurality of auxiliary plungers adapted to be supplied with pressure fluid from said pump to hold a work piece during the cutting operation, yielding means continuously tending to space said auxiliary plungers from said work piece, further conduit means interconnecting the retraction sides of said main plungers, first control valve means hydraulically connected with said auxiliary plungers for preventing supply of pressure fluid to the advancing sides of said main plungers prior to the establishment of a predetermined pressure on said auxiliary plungers, second control valve means for preventing the escape of fluid from the retraction sides of said main plungers prior to the establishment of a predetermined pressure on the advancing sides of said main plunger, and by-pass valve means for bypassing said first and second control valve means during the retraction stroke of said main plungers.

14. In a hydraulic system, the combination of a hydraulic hold-down means, a hydraulically operable shear, and means to bring about the actuation of the shear upon the accomplishment of a predetermined pressure on said hydraulic hold-down means.

15. In a hydraulically operable shear, a main plunger having associated therewith fluid operable advancing and retracting means for reciprocating said main plunger, a fluid operable auxiliary plunger, conduit means hydraulically interconnecting said advancing means and said auxiliary plunger, and means arranged in said conduit means and responsive to a predetermined pressure on said auxiliary plunger for effecting hydraulic communication between said advancing means and said auxiliary plunger.

WILLIAM J. RIDDLE.
